WASH BASIN SHELF

Guy Vrignaud, Grenoble, France, assignor to Allibert
Exploitation Societe Anonyme, Puteaux, France

Filed Nov. 6, 1974, Ser. No. 521,484

Claims priority, application France May 6, 1974

Term of patent 14 years

Int. Cl. D6—04

U.S. Cl. D6—136

FIG. 1

FIG. 3

FIG. 2

FIG. 4

FIG. 5

FIG. 6

FIG. 1 is a perspective view of a wash basin shelf showing my new design;

FIG. 2 is a front elevational view thereof;

FIG. 3 is an end elevational view thereof, the other end elevational view being identical;

FIG. 4 is a top plan view thereof;

FIG. 5 is a bottom plan view thereof; and

FIG. 6 is a rear elevational view thereof.

I claim:

The ornamental design for a wash basin shelf, as shown and described.
